UNITED STATES PATENT OFFICE

117,525

DESIGN FOR A DRESS

Margaret Michelson, New York, N. Y.

Application October 16, 1939, Serial No. 87,666

Term of patent 3½ years

To all whom it may concern:

Be it known that I, Margaret Michelson, a citizen of the United States, residing in New York city, in the county of New York and State of New York, have invented a new, original, and ornamental Design for a Dress, of which the following is a specification, reference being had to the accompanying drawing, forming part thereof.

Fig. 1 is a front view of a dress showing my design, and

Fig. 2 is the rear view thereof.

I claim:

The ornamental design for a dress, substantially as shown.

MARGARET MICHELSON.
